(57) **CLAIM**

The ornamental design for the food storage tray, as shown and described.

DESCRIPTION

FIG. 1 is a perspective view of the food storage tray with the plurality of lids in a closed configuration;

FIG. 2 is an exploded perspective view of the food storage tray and the plurality of lids in an open configuration;

FIG. 3 is a top plan view of the food storage tray of FIG. 1; FIG. 4 is a cross-sectional view of the food storage tray along 4-4 of FIG. 3;

FIG. 5 is a bottom plan view of the food storage tray; and, FIG. 6 is a front view of the food storage tray of FIG. 1, with the rear and side views being identical to the front view.
